US00D600051S

(12) **United States Design Patent**
Parker et al.

(10) **Patent No.:** US D600,051 S
(45) **Date of Patent:** ** Sep. 15, 2009

(54) **CHAIR BACK**

(75) Inventors: **Kent Wallace Parker**, Lower Hutt (NZ);
Daryl Owen Neal, Lower Hutt (NZ)

(73) Assignee: **Formway Furniture Limited**,
Wellington (NZ)

(**) Term: **14 Years**

(21) Appl. No.: **29/306,463**

(22) Filed: **Apr. 9, 2008**

(51) LOC (9) Cl. **06-01**

(52) U.S. Cl. **D6/502**

(58) Field of Classification Search D6/500-502,
D6/364-367, 369, 379-380; 297/411.27,
297/411.36, 411.29, 411.46, 411.64, 284.4,
297/300.2, 452.3, 411.2

See application file for complete search history.

(57) **CLAIM**

The ornamental design for a chair back, as shown and described.

DESCRIPTION

FIG. 1 is a top plan view of a chair back showing our new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a perspective view thereof.

The broken lines are for illustrative purposes only and form no part of the claimed design.
